LOCKING GAS CAP

Richard S. Hart, Glen Ellyn, Ill., assignor, by mesne assignments, to Allen Electric and Equipment Company, Kalamazoo, Mich., a corporation of Michigan

Filed June 9, 1964, Ser. No. 80,337

Term of patent 14 years

(Cl. D14—18)

Fig. 1.

Fig. 2.

Fig. 3.

Fig. 4.

FIG. 1 is a top plan view of a locking gas cap, showing my new design;

FIG. 2 is a side view in elevation thereof;

FIG. 3 is a bottom view thereof; and

FIG. 4 is a vertical sectional view thereof taken along line 4—4 of FIG. 1.

The dominant features of the design are shown in solid lines.

I claim:

The ornamental design for a locking gas cap, substantially as shown and described.
